P. STOREY.
SEAL LOCK.
APPLICATION FILED OCT. 14, 1915.

1,173,056.

Patented Feb. 22, 1916.

THE COLUMBIA PLANOGRAPH CO., WASHINGTON, D. C.

UNITED STATES PATENT OFFICE.

PAUL STOREY, OF TAFT, BRITISH COLUMBIA, CANADA.

SEAL-LOCK.

1,173,056.

Specification of Letters Patent. Patented Feb. 22, 1916.

Application filed October 14, 1915. Serial No. 55,838.

To all whom it may concern:

Be it known that I, PAUL STOREY, a citizen of the United States, and a resident of Taft, in the Province of British Columbia, 5 Dominion of Canada, have invented certain new and useful Improvements in Seal-Locks, of which the following is a specification.

My invention relates to seals for the doors of railway freight cars, and some of the 10 main objects thereof are to provide such devices which are quickly and easily sealed, wherein there is no possibility of removing the sealing medium without destroying the same, which are highly efficient, and which 15 are comparatively inexpensive.

My invention is fully described in the following specification, of which the accompanying drawings form a part, in which like characters refer to like parts in each of the 20 views, and in which:—

Figure 1 is a fragmentary view of a car door and the frame therefor, with my invention in sealed position; Fig. 2 is a section taken on the line 2—2 of Fig. 1; Fig. 3 is 25 a fragmentary face view showing the manner of applying the sealing medium; Fig. 4 is an edge view of the tool which I employ for applying the seal; Fig. 5 is a plan view of the sealing medium; Fig. 6 is a section 30 taken on the line 6—6 of Fig. 5; and Fig. 7 is a section taken on the line 7—7 of Fig. 1.

In the drawings forming a part of this application I have shown, fragmentarily, the side 7 of a car and its door 8, upon each 35 of which a portion of my device is arranged.

A base block 9 is held on the side of the car by means of a bolt 10 provided with an angular head 11 resting in a similarly formed recess 12 in the block 9; the block 9 40 is provided with a plurality of projections 13 extended into the side of the car, Fig. 2, and it will be obvious that, when the nut 14 of the bolt is tightened, said block cannot move with respect to the side of the car and said 45 bolt cannot rotate with respect to said block. The block 9 is provided with four upwardly extending arcuate flange members 15, 16, 17, and 18, arranged concentric with the axis of the bolt 10 and producing radial passages 50 19, 20, 21, and 22, between the respective flange members at quadrant points as shown, said flange members producing a circular recess 23 within the same.

Held by a bolt 24, adjacent to the block 55 9, is a staple 25 arranged in the horizontal

plane of the center of the block 9, the opening through said staple thus being transverse to the said horizontal plane, but this staple is not an essential part of the invention and is shown to indicate an arbitrary 60 use of the device, or rather an alternate or supplemental use thereof.

An eye-bolt 26 is held in the door 8 and serves as a pivot for a hasp 27 which comprises a relatively thin portion 28, a thickened portion 29, and a handle portion 30, the portion 29 having a recess 31 in the upper surface thereof which registers with the contiguous sections of the recess 23, as is clearly shown in Fig. 2. The raised portions of the 70 hasp at each side of the recess 31 rest within the radial passages 19 and 21 and fill the same, being flush with the upper surfaces of the flange members 15, 16, 17 and 18. The inner surfaces of these raised portions 75 29 are grooved adjacent the floor of the recess 31, and the inner surfaces of the said flange members are similarly grooved adjacent the floor of the recess 23, Fig. 7, the former grooves being shown at 32 and the latter grooves at 33, these grooves registering with each other to form a substantially 80 continuous groove intercepted by the radial passages 20 and 22.

The sealing medium or element consists of 85 a metal disk 34 of an external diameter approximating the internal diameter of the combined recesses 23 and 31 and into which said disk is designed to be forced. The disk 34 is provided with two ribbon members 35 90 and 36 arranged at diametrically opposite points, and with arcuate raised flanges 37 extending, each, from one ribbon to the other, these flanges 37 being of approximately 95 the same height as the flange members of the base block and as the height of the portions 29 of the hasp.

As stated, the hasp is arranged in the passages 19 and 21 and in the groove connecting the same shown in Fig. 7, and I provide 100 downwardly directed lugs 38 on the under side of the hasp for preventing longitudinal movement of said hasp with respect to the block 9, as clearly shown in Fig. 2. When the hasp is in position within the base block 105 9 one of the disks 34 is inserted into the space formed by the recesses 23 and 31, the ribbon members 35 and 36 being arranged in the radial passages 20 and 22, the exterior 110 surfaces of the flanges 37 bearing on the

inner surfaces of the flange members 15, 16, 17, and 18, and of the portions 29 of the hasp.

A tool 39 is provided for crimping the flanges 37 into the grooves 32 and 33 consisting of a handle 40 having a yoke 41 at one end thereof, each arm of which carries a pin 42 for a roller 43 having its periphery curved to approximately fit the curvature 10 of the grooves 32 and 33, and the diameter of the crimper from the outside edge of one roller 43 to the outside edge of the other roller is two thicknesses less, of the tin or other material of which the flanges 37 are 15 made, than the maximum diameter of the combined recesses 23 and 31, whereby said crimper approximately fills the grooves, at opposite sides of the recesses, and thus crimps the flanges 37 into said grooves when said 20 crimper is revolved with respect to the base block. The inner ends of the radial passages 20 and 22 are slightly flared, as shown at 44, Fig. 3, to admit the crimper, this flaring occurring at the spaces between the 25 respective ends of the flanges 37 of the sealing element. When the flanges have been thus crimped, the crimper is removed and no outward movement of the hasp with respect to the base block 9 is possible except by the 30 destruction of the sealing medium, and I may, if desired, stamp any suitable matter on the sealing disk or on its ribbons to identify the same to prevent unauthorized substitution of one sealing element by another except by making such substitution manifest. If desired, the ribbon members 35 and 36 may be passed through the opening of the staple 25 and sealed together in the conventional manner by means of the 40 lead seal 45. When it is desired to open the car door, all that is necessary is to apply outward force to the handle of the hasp 27, this tending to force the relatively thin sealing element upwardly through the radial 45 passages 19 and 21 and rendering the same utterly unfit for further use, and it will be understood that the proper railway officials will be provided with a stock of the sealing elements, each, as well as with a crimper.

50 My invention is very simple though highly efficient and, while I have shown a present preferred form, it will be obvious that changes may be made therein to meet different conditions, within the scope of the following claims, without departing from the spirit of the invention or sacrificing its advantages.

Having fully described my invention, what I claim as new, and desire to secure by 55 Letters Patent, is:—

1. A seal lock, comprising a base block having a circular recess the wall of which is peripherally grooved, a hasp resting in said

recess, and a sealing element in said recess above said hasp having a flange crimped 65 into said groove.

2. A seal lock, comprising a base block having a circular recess the wall of which is peripherally grooved, a hasp resting in said recess, means for preventing movement of 70 said hasp laterally of said block, and a sealing element in said recess for preventing removal of said hasp from said prevention means provided with a flange crimped into said groove.

3. A seal lock, comprising a base block having a circular recess formed by flange members spaced to form passages therebetween, and peripherally grooved on their inner surfaces, a hasp resting in said recess 80 and in the respective passages, and a sealing element in said recess above said hasp provided with a flange crimped into said groove.

4. A seal lock, comprising a base block 85 having a circular recess formed by flange members spaced to form passages therebetween and peripherally grooved on their inner surfaces, a hasp resting in said recess and in the respective passages provided with 90 raised portions grooved in their inner surfaces to form a continuous groove with those of the adjacent flange members, and a sealing element in both said recess and between said raised members provided with a flange 95 crimped into said grooves.

5. A seal lock, comprising a base block having a circular recess formed by flange members spaced apart to form passages therebetween and peripherally grooved on 100 their inner surfaces, a hasp resting in said recess and in the respective passages, provided with raised portions grooved in their inner surfaces to form a continuous groove with those of said flange members, and a sealing element provided with a flange 105 crimped into said grooves, said element being provided with ribbon members resting in the respective ones of said passages.

6. In a seal lock, a sealing element consisting of a disk of sheet material provided with a peripheral flange adapted to be outwardly crimped to engage the corresponding parts of said car seal.

7. In a seal lock, a sealing element consisting of a disk of sheet material provided with diametrically opposite ribbon members and with diametrically opposite peripheral flanges between said ribbon members.

In testimony whereof I have signed my name to this specification in the presence of two subscribing witnesses.

PAUL STOREY.
